UNITED STATES PATENT OFFICE.

GEORGE W. BANKER, OF BROOKLYN, NEW YORK.

FAUCET FOR OIL-CANS.

SPECIFICATION forming part of Letters Patent No. 359,704, dated March 22, 1887.

Application filed February 2, 1887. Serial No. 226,216. (No model.)

To all whom it may concern:

Be it known that I, GEORGE W. BANKER, of Brooklyn, county of Kings, State of New York, and a citizen of the United States, have 5 invented certain new and useful Improvements in Faucets for Oil-Cans, of which the following is a full, clear, and exact description, reference being had to the accompanying drawings, forming part of this specification.

10 My invention relates to a faucet-nozzle of cans adapted to hold oil or other fluids; and my invention consists in the hereinafter-described improvements upon the faucet-screw for which Letters Patent were granted March 15 25, 1884, No. 295,794, to Michael O'Connor.

Figure 1 is a side elevation of a faucet containing my improvements, and Fig. 2 is a vertical central sectional view of the same.

Similar letters indicate corresponding parts. 20 A is the metallic plate which serves to attach the faucet device to a metal can.

B is the sheet-metal screw-socket, the inner or lower end of which is enlarged so as to form a chamber, b, from which extends the discharge-spout b'. The plate, the chamber, and the screw-socket are preferably all formed of one and the same piece of sheet metal.

C is the valve, the body of which is a sheet-metal screw-stem, c. On the inner or lower 30 end of the stem c is a disk or flange, c', which may be of the same piece of metal with said stem. Upon this disk or flange is placed and supported the packing-piece c''. The screw-stem fits into the screw-socket B. Upon the 35 upward or outer end of the stem c is a thumb-piece, c³, fixed thereto, by means of which the stem and its valve are operated to be screwed up and down in the socket, and the valve to be thus opened and closed. When the thumb-piece is turned so as to open the valve, the 40 chamber b is opened all round, and the oil or other contents of the can passes freely to the discharge-spout.

My improvements on the screw-faucet above 45 described, which is substantially that shown in the Letters Patent No. 295,794, hereinbefore mentioned, are as follows:

E is a chamber formed on the plate A contiguous to the chamber b, and communicating therewith through an opening, b², in the wall 50 of the chamber b, as shown. This chamber E

has an opening in its outer wall, as at e, leading externally of the device, as shown. By this means I provide an air vent or inlet to the faucet, thus improving the discharge of 55 the oil through the chamber b and spout b', and at the same time preventing the oil from escaping through the air-vent when the can is being emptied to the exterior of the can, any oil which may pass through the vent b² 60 being caught in the chamber E, and flowing back thence through said opening b² into the chamber b, and thence to the body of the can. The venting of the faucet is thus accomplished at the same time that the soiling of the exterior 65 of the faucet and can by the escape of the oil at the vent is prevented.

My further improvement consists in a flat collar, F, fixed upon the stem c and placed at such a distance above the disk or flange c' 70 relatively to the thickness of the packing-piece c'' that said packing-piece lies loosely between the said collar and flange, and has vertical play on the stem between said collar and flange. I prefer to form an annular corrugation or rib, f, on the under or inner side of the plate A, arranged to engage against the upper face of the packing-piece c''. By means of this arrangement of the packing-piece, when the valve is closed, said packing-piece will not 80 be rotated with the stem and the flange c', as it would if tightly clamped between and held by said flange and a cap on the stem impinging on the packing; but said packing-piece when brought up against the plate A will remain stationary while the stem and flange c' 85 are further rotated to tighten the valve on its seat, whereby the wear of the packing-piece by friction against the valve-seat is avoided.

What I claim as my invention, and desire 90 to secure by Letters Patent, is—

1. In a vented screw-faucet for fluid-holding vessels, the combination, with the attaching-plate A, giving the valve-seat, the screw-socket B, the chamber b, directly at the inner end of 95 said socket and having spout b', and the threaded valve-stem c, carrying valve C, arranged to play in said socket, of the chamber E, contiguous to said chamber b, and communicating therewith by opening b², and having an air-vent, e, as described, and for the purpose 100 set forth.

2. In a screw-faucet for fluid-holding vessels, the combination, with the attaching-plate A, giving the valve-seat, the screw-socket B, and the chamber b, directly at the inner end of said socket and having spout b', of the threaded valve-stem c, arranged to play in said socket, and having on its inner end the disk or flange c', and above such flange the fixed collar F,

and the packing-piece c², seated loosely between said flange and collar on said stem, as to described, and for the purpose specified.

GEO. W. BANKER.
